PICTURE FRAME OR THE LIKE

Harvey A. Prew, North Kingston, R. I., assignor
to Pru-les-co Art Metal Co., Inc., a corporation
of Rhode Island

Application July 30, 1940, Serial No. 348,330

1 Claim. (Cl. 40—152)

This invention relates to a picture frame or like article, and has for one of its objects to provide a picture frame from which the glass will not fall to become broken regardless of the presence of a backing member.

Another object of the invention is to provide by a simple means an arrangement for holding the glass of a picture frame in place and yet permitting a back to be slid from position and entirely removed and the frame tilted or moved about without the backing with no danger of the glass dropping from the frame.

With these and other objects in view, the invention consists of certain novel features of construction, as will be more fully described, and particularly pointed out in the appended claim.

In the accompanying drawing:

Fig. 1 is a plan view of the frame with glass therein;

Fig. 2 is a similar view of the back;

Fig. 3 is a section on line 3—3 of Fig. 1;

Fig. 4 is a perspective view of a fragmental portion of Fig. 3;

Fig. 5 is a section at right angles to the section of Fig. 3 through the lower portion of the frame as shown in Fig. 4; and

Figure 6 is a side elevation view of a fragmentary portion of the frame.

Some inexpensive pictures are mounted by means of a metal frame surrounding a glass with the picture back of the glass and a backing back of the picture, and it frequently occurs that when the backing is removed, the glass may drop from the frame; in such arrangements the glass has been so frequently broken that stores do not care to handle frames so constructed; and in order to obviate this difficulty, I have provided an arrangement of such frame whereby the glass cannot drop from the frame even though the backing is entirely removed by a simple manipulation of the open edge of the frame utilizing a portion of the stock which has heretofore been removed; and the following is a more detailed description of the present embodiment of this invention, illustrating the preferred means by which these advantageous results may be accomplished:

With reference to the drawing, 10 designates a sheet of glass, 11 a picture which may be placed back of the piece of glass, and 12 a cardboard backing of sufficient thickness so as to be relatively stiff although somewhat soft and compressible. A frame designated generally 14 is formed of a strip of channel stock, usually metal, comprising a bridging wall 15, a front side wall 16, a back side wall 19 and a top side wall 23.

16, shaped in an ornamental fashion by curvatures 17 and 18 and a back side wall 19 and with the extreme free edge of the portion 18 bent inwardly to provide a narrow glass engaging surface. This channel-shaped stock has its front side wall 16 and back side wall 19 notched so that the bridging wall 15 may be bent for the formation of corners as at 20, the notch being a 90-degree V in both of these walls. These notches permit of the bending at the corners to provide the four sides of the frame to provide the opposite vertical sides 22 and top side 23 and bottom side 24.

The opposite sides 22 and the top side 23 will all be formed as I have illustrated at the top of Fig. 3, but the bottom side 24 will be differently formed and instead of the back wall 19 being spaced a sufficient distance so that it will just accommodate and cause the glass 10, the picture 11 and the backing 12 to be pressed firmly into engagement, this back wall designated 25 will be rolled inwardly so that the bridging wall 26 will be of shorter width and the distance between the front side wall 14 and the back side wall 25 of this lower side will be such that it will just receive the glass 10. Thus, this back side wall 25 will extend between the glass and the backing member and the picture along the extent of the lower side 24. By this arrangement the back 12 and the picture 11 may be slid from the frame and from beneath the side wall 19 of the top side 23 and the walls 19 of the sides 22, but the glass by reason of the rolling inwardly of the back wall 19 cannot be removed from position 35 unless the frame is detached and taken apart.

By the provision of this arrangement, after the usual channel as described at the top of Fig. 3 is formed, I roll inwardly the wall 25 over the glass so that it extends upwardly further than heretofore and locks the glass in place. By this arrangement I am able to make an unacceptable frame acceptable in a very inexpensive construction.

I claim:

45 A generally rectangular picture frame or the like comprising a sheet of glass and a cardboard backing therefor, a frame comprising channel stock on the four sides thereof having spaced walls providing front and rear walls and with the extreme edge portions of said front walls having a bend therein extending towards the rear walls and providing a narrow glass-engaging surface, the narrow glass-engaging surface and the opposite walls of the channel stock engaging the outer surfaces of the glass and cardboard

along the marginal edges of the top and two sides of the frame and the spaced walls of the bottom part of the frame being closer together than the other spaced walls and engaging only the opposite surfaces of the glass with one wall located between the glass and cardboard, the

width of the opposite side walls of the frame being such as to block swinging of the glass from between them whereby the cardboard may be slid from position in the frame while the glass is retained therein.

HARVEY A. PREW.
